(57) **CLAIM**

The ornamental design for a remote control for irrigation controller, as shown and described.

DESCRIPTION

FIG. 1 is a top, front and side perspective view of a remote control for irrigation controller embodying the new design.

FIG. 2 is a top, back and side perspective view thereof.

FIG. 3 is a front view thereof.

FIG. 4 is a back view thereof.

FIG. 5 is a top view thereof.

FIG. 6 is a bottom view thereof.

FIG. 7 is a side view thereof; and,

FIG. 8 is a side view thereof opposite the side view of FIG. 7. Broken lines are used to illustrate features of the remote control for irrigation controller which form no part of the claimed design.

1 Claim, 6 Drawing Sheets

FIG. 1

FIG. 2

FIG. 3

FIG. 4

FIG. 5

FIG. 6

FIG. 7
